UNITED STATES PATENT OFFICE.

CARL E. SCHULTZE, OF NEW YORK, N. Y.

DESIGN FOR A DOLL.

SPECIFICATION forming part of Design No. 36,564, dated September 22, 1903.

Application filed April 28, 1903. Serial No. 154,726. Term of patent 3½ years.

To all whom it may concern:

Be it known that I, CARL E. SCHULTZE, a citizen of the United States, residing at the city, county, and State of New York, have invented a new, original, and ornamental Design for Dolls, of which the following is a specification, reference being had to the accompanying drawings, forming part thereof.

Figure 1 is a front view of the doll. Fig. 2 is a rear view of the doll; Fig. 3, an edge view.

Now having fully described my invention,

what I claim as new, and desire to secure by Letters Patent, is—

The ornamental design for a doll as herein shown.

In testimony whereof I have signed my name to this specification in the presence of witnesses.

CARL E. SCHULTZE.
